UNITED STATES PATENT OFFICE

SYLVANUS W. FISK, OF LOS ANGELES, CALIFORNIA

DISHWASHING MACHINE

Application filed March 22, 1929. Serial No. 349,011.

This invention relates to a rotator for a dish washing machine; and it is an improvement on the washing machine disclosed in the application for United States Letter Patent filed January 30, 1929, Serial Number 336,069.

The principal object of this invention is to improve the rotator of the washing machine so it is more simple to construct and assemble and which is more efficient in picking up the liquid from the bottom of the receptacle and discharging it with great force upwardly into a chamber in which the articles to be cleansed are located.

15 Features of invention are shown in the construction, combination and arrangement of the spaced disks and associated parts whereby a rotator is provided that is easy to construct, assemble and operate, which also is effective to pick up the water below the longitudinal axis of the rotator shaft and throw it radially above the shaft.

20 Other objects, advantages and features of invention may appear from the accompanying drawings, the subjoined detailed description and the appended claims.

The accompanying drawings illustrate the invention, in which:

Fig. 1 is a side view of a dish washing machine constructed in accordance with this invention, parts indicated semi-diagrammatically, with the doors in closed position, and their open positions indicated by dotted lines.

25 Fig. 2 is an end view of the machine, with the doors in open position.

Fig. 3 is an enlarged fragmental section on line 3—3, Fig. 2, showing the doors in closed position and also showing a side view of the rotators and motor; and baskets of dishes in each upper chamber.

30 Fig. 4 is a fragmental section on line 4—4, Fig. 3, showing the arrangement of the slat partition between the upper and lower chambers.

45 Fig. 5 is a fragmental section on line 5—5, Fig. 3, showing a plan view of the slat partition.

Fig. 6 is an enlarged cross section on the line 6—6, Fig. 3, with parts omitted showing 50 a detailed construction of one of the rota-

tors; and also showing a round shaft on which the disks of the rotator are mounted.

Fig. 7 is a fragmental view of one of the rotators as viewed from line 7—7, Fig. 6, showing the arrangement of the disks on the 55 shaft.

Fig. 8 is a central section on line 8—8 of Fig. 6.

Fig. 9 is an enlarged fragmental cross section through the washing machine on line 60 9—9, Fig. 3, illustrating by feathered arrows the direction of rotation of the rotators, and showing by the short arrows how the rotator picks up the liquid from the bottom of the lower chambers and throws it upward 65 through the slat partitions into the upper chambers.

Fig. 10 is a side view of a disk as cut out of a square sheet metal blank showing the scoops integral with the disk edge before they 70 are bent to proper form; also showing a round center bearing for mounting the disks on the shaft.

Fig. 11 is a fragmental side view of a rotator analogous to the center portion of Fig. 75 6, showing a square shaft on which the disks are mounted.

The washing machine includes a receptacle formed of a bottom 10, end walls 11, 12, a center wall 13 and side walls 14, 15 80 that are secured together and supported on legs 16, 17.

The side walls 14, 15 are extended upward above the end and center walls, and are secured together by a top plate 18, which, together with the sliding end doors 19, 20 and sliding center doors 21, 22 form upper chambers into which wire baskets 23 containing dishes 24 can be extended and supported on 90 the slat partitions 25.

The slat partitions 25 are supported on angle irons 26 secured to the end walls 11 and 12 and center partition 13, and the slats are spaced a considerable distance apart so 95 that liquid 31 can be thrown from the lower chambers 29, 30 through the partition into the upper chambers 32, 33 so as to wash and rinse the dishes in the baskets. The foregoing parts are all old except the rotators and 100

are shown only for the purpose of illustrating the operation of the rotators.

The rotators 27, 28 are constructed and operated alike. Each includes a number of 5 disks 34 that are secured on a shaft 35 having its ends journaled in the end walls 11, 12 and extended through the center wall 13 of the machine, as indicated in Figs. 1 and 3.

The disks 34 are spaced from the walls 11, 10 12 and 13 by washers 36, and are spaced apart from one another by the scoops 37 and radial arms 38. The outer ends of the arms 38 are bent into cylindrical sleeves 39 through which the tie rod bolts 40 are extended, and 15 these rods also extend through holes 41 in the disks 34 and are secured in place by nuts 42.

The arms 38 are arranged tangentially to the shaft 35 and have flanges 43 at their inner end that are secured by rivets 44 to the 20 adjacent arms 38 so as to form a rectangular bearing around the shaft to pinchingly engage it so that they rotate together.

If desired the shaft 35 can be square, as 25 shown in Fig. 11, in which instance the center openings 45 in the disks 45 would also be squared to fit it.

The disks 34 are formed of sheet metal blanks, as indicated by the rectangle enclosed by the dotted lines 46. These disks 30 are cut out of the metal blanks so that each has the scoops 37 integral with the peripheral edges of the disks; and these scoops are then bent over so that they extend at right angles to the disks.

35 Each scoop 37 is provided with an integral flange 47 that extends rearwardly and terminates in a tail piece 48 that is secured by rivets 49 to the disk, each disk being provided with spaced rivet holes 50 for that purpose, as shown best in Figs. 6 and 10.

A plain disk 51 is arranged at the terminal end of each rotator and they are the same diameter and formed like the other disks except that they do not carry the scoops 45 37, see Figs. 3 and 8.

The scoops 37 are arranged so that when the shaft 35 is rotated they will pick up a charge of the liquid 31 as they enter it and force is inwardly toward the axis of the 50 shaft into the spaces between the inside of the scoops and the rear side of the radial arms; and when the scoops are turned to a position clear of the body of the liquid 31 the charges begin to discharge by centrifugal force from the spaces between the front sides of the radial arms and the rear sides of the scoops, as illustrated by the short arrows in Fig. 9.

The liquid 31 either for washing or rinsing 60 the dishes 24 is filled into the lower chambers 29, 30 until it reaches a level slightly above the shaft 35; and the scoops of the rotators are arranged so that when in operation they pick up substantially all of the liquid 65 and discharge it into the upper chambers 32,

33, it being understood that the rotators 27 and 28 are driven at high speed so that they pick up the liquid very rapidly and throw it with great force into the upper chambers.

The shaft 35 is driven by a motor 52 secured by bolts 53 to the bottom 10 and it is connected to the shaft 35 by a chain drive 54 enclosed in the housing 55, as indicated in Figs. 1, 2 and 3.

Platforms 56, 57 are secured to the ends of 75 the washing machine to facilitate placing baskets of dishes in and removing them from the machine, and the doors are provided with handles 58, 59, 60, 61 so they can be raised or 80 lowered when necessary.

In operation the lower chamber 27 is charged with a liquid solution suitable for washing dishes, and also the chamber 30 is charged with a liquid suitable for rinsing 85 them after they are washed. Then the door 19 is opened and a wire basket filled with soiled dishes is placed on the slat partition 25, in the chamber 32, and the door again closed.

Then the motor 52 is started and driven 90 until the dishes in chamber 32 are thoroughly washed. Then the doors 19, 21 and 22 are opened and the basket of washed dishes is moved into the chamber 33, and another basket of soiled dishes is placed in chamber 32. 95 Then with the doors closed, the motor is again started to wash the dishes in the chamber 32 and rinse the dishes in the chamber 33. Then when these baskets of dishes are properly treated all the doors of the machine are 100 opened so that the basket of rinsed dishes can be removed and the washed dishes transferred from the chamber 32 to chamber 33, so another basket of soiled dishes can be placed in the chamber 32. Then all the 105 doors are closed and the motor again started to repeat the process of washing and rinsing baskets of dishes in successive order as described.

110 I claim as my invention:

1. A rotator for a dish washing machine including a shaft having its ends journaled in the end walls of the machine, disks on said shaft, washers on said shaft for spacing the end disks from the end walls, radial arms arranged to space said disks apart, scoops secured to said disks so as to pick up charges of liquid from the bottom of said washing machine and move it into position to be thrown by said radial arms when said shaft is rotated, and means for rotating said shaft.

115 2. A rotator for a dish washing machine including a shaft having its ends journaled in the end walls of said machine, disks on said shaft that are spaced away from the end walls of said receptacles by washers on said shaft, radial arms arranged to space said disks apart, scoops integral with the peripheral edges of said disks, rearward extensions integral with said scoops that are 120 125 130

secured to said disks, said scoop arranged to pick up charges of liquid in the bottom of said machine and force it inwardly toward the axis of said shaft, and said radial arms 5 arranged to throw the charges of liquid away from the axis of said shaft when said shaft is rotated, and means for rotating said shaft.

3. A rotator for a dish washing machine including a shaft having its ends journaled 10 in the end walls and extended through a center wall of said machine, disks mounted on said shaft, washers on said shaft spacing the adjacent disks from the end and center walls of said receptacle, radial arms arranged to 15 space said disks apart, sleeves on the outer ends of said arms, rod bolts passing through said disks and sleeves for securing said disks and arms together, scoops integral with the peripheral edges of said disks that are ex- 20 tended at right angles to the sides of said disks, rearward extensions to said scoops that are bent inwardly toward the axis of said shaft, tail pieces on the free ends of said ex- 25 tensions that are secured to the sides of said disks, and a motor for driving said shaft at high speed so that said scoops will pick up charges of water and direct it toward said radial arms so they will throw the water from the lower into the upper part of said 30 machine for the purpose specified.

In witness whereof, I have hereunto affixed my signature.

SYLVANUS W. FISK.
